VOLUME CONTROL MEANS FOR
RADIO APPARATUS

Edward Washburn Kellogg, Moorestown, N. J., assignor, by mesne assignments, to Radio Corporation of America, New York, N. Y., a corporation of Delaware

Application May 28, 1931, Serial No. 540,690

4 Claims. (Cl. 250—20)

My invention relates to radio receiving apparatus and the like, having a sound producing output system which may be subjected to strong signals and thereby produce excessively loud sounds when the apparatus is in operation, and more particularly it relates to a volume control means therefor adapted to limit the sound output from the sound producing system.

It is well known that in tuning modern high-gain radio receivers to distant and weaker signals or stations in the presence of strong local signals and the like, that excessively loud bursts of sound from the output system or loudspeaker may often be unavoidably produced as the tuning control means is carried through positions for receiving such local stations or signals.

It is also well known that means have heretofore been provided for automatically varying the sensitivity of radio receiving apparatus and the like to signals in accordance with their strength, whereby a more constant output sound level is maintained. Such systems are known as automatic volume control systems, and while functioning to prevent excessively loud sound output from the sound producing system of a radio receiving apparatus, may generally be characterized as relatively costly and complicated, with the result that heretofore the use of such automatic volume control means has not been as extensive as its results would warrant.

It is, therefore, an object of my invention to provide a control means for preventing excessively loud sounds during tuning of radio receiving apparatus and the like, which is simple in character and relatively low in cost, whereby it may have a wide application to such apparatus.

It is a further object of my invention to provide a volume control means of the above character which is adapted to be responsive to a tuning operation of a control means of radio receiving apparatus and the like, to effectively reduce the signal output therefrom during such operation and with no conscious effort on the part of the operator.

Thus, in accordance with my invention, there may be provided means adapted to control the signal output amplitude from a radio receiving system during movement of the tuning control means when the same is moved in the normal direction of operation, e. g. to prevent strong signals from producing excessively loud sounds in the sound producing element of the system.

Further in accordance with my invention I have provided means in radio receiving apparatus for automatically limiting the amplification or

volume of signal reproduction during the operation of program or station selection, while permitting sufficient volume output to enable the operator to identify the programs or stations, and for rendering the limiting action ineffective after completion of said operation.

It would be possible to accomplish the purposes already set forth, by means of a switch, either separately manually operated, or operated by means of an extra movement of the tuning knob, such for example as an axial movement, but such an additional operation requires conscious effort, and may be inadvertently omitted with resulting disagreeable loud sounds. Accordingly it is one of the objects of my invention, to accomplish the necessary circuit changes automatically by the same operation and movement as is required for the purpose of tuning.

Other objects of my invention will become evident from the following detailed description taken in conjunction with the accompanying drawing in which,

Fig. 1 is a view, in perspective, of radio tuning apparatus provided with a control device embodying the invention;

Fig. 2 is a side elevation view, partly in section, of the device shown in Fig. 1 and on the same scale;

Fig. 3 is a schematic circuit diagram of a radio receiving system illustrating the application thereto of the control device shown in Figs. 1 and 2;

Fig. 4 is a further schematic diagram of a thermionic amplifier also showing the application thereto of the device embodying my invention;

Fig. 4a shows another modification of a radio receiving apparatus to which the control device of Figs. 1 and 2 may be applied; and

Fig. 5 is a view in perspective of a modified form of a control device embodying my invention.

Referring to Figs. 1 and 2 of the drawing, tuning apparatus 1 for a radio system comprises a plurality of tuning condensers 3 and 5 mechanically connected as by a shaft 19 for simultaneous operation and adapted to be driven as by means of a tuning or control knob 7 and a control shaft 9. The latter is provided with a driving sheave or spindle 11 upon which is wound a belt or cord 13 for driving a drum 15 and an indicating or tuning dial 17, both of which are secured to the condenser shaft 19. This arrangement provides for the operation of the tuning or control means 1 of the apparatus by the control knob 7 through the medium of the control shaft 9 and 55

the wrapped cord connection and is merely illustrative of one form of control means for radio apparatus to which a control device and circuit embodying my invention is applicable.

5 A clutch means indicated at 21 is provided between the tuning mechanism 1 and a switch 29 as an operating connection for the switch whereby the latter is caused to operate during a tuning motion of, and in response to, the motion of the 10 tuning mechanism. One member 23, of the clutch, is secured to the actuating or control shaft 9, whereby it moves in response to movement of the tuning control means. The clutch member 23 is in the form of a casing surrounding 15 the plate or disk 27 as the driven element of the clutch. The elements are coaxial and are located in spaced relation to each other as indicated. The driving connection between them is provided preferably by a viscous fluid such as a 20 heavy oil indicated at 35 which fills the casing or driving element and surrounds the driven element whereby motion of the driving element 23 causes the driven element 27 to follow, but permits a return movement of the driven element 25 27 under the action of a restoring force provided by means hereinafter described.

This type of clutch connection is one in which the force depends upon relative velocity and offers little, if any, static friction and for purposes of 30 the invention has advantages which will herein-after be pointed out. This type of clutch has advantages over an ordinary friction clutch. In the latter the force transmitted to the driven element does not drop to zero when the relative motion ceases, and if used, the switch 29 would not 35 return to normal position, or the reaction on the driving element might cause it to shift after the operator's hand is removed from the driving knob. The above viscous connection has the advantage, 40 as compared with ordinary rubbing friction, that all force reaction between the driving and driven elements vanishes after cessation of the driving motion.

The housing or driving element of the clutch 45 comprises a dished plate member 23 having a cover disc 24 secured across its open face, and a bushing 31, as of leather, interposed between a central aperture in said cover disc and the shaft 33 which actuates the switch. The bushing 31, however, should be sufficiently free to avoid causing 50 any appreciable rubbing friction on the shaft 33, and be at the same time substantially a liquid-tight container.

There are a number of well known extremely 55 viscous materials which might be employed for this clutch. Some of these are colloidal in nature. The primary requisites are that the material used shall not congeal at the lowest temperature at which the device is to be employed, and that it 60 shall be permanent. It should not, for example, depend for its fluidity upon the presence of solvents which may be lost through evaporation. One especially suitable material is a solution of rubber in mineral oil.

65 The driven element 27 of the clutch comprises a circular disc secured to the shaft 33 on which is mounted the movable element of the electric switch 29, or equivalent device. This movable switch element comprises a hub 37 and an arm 70 39 carrying a contact element 41, preferably insulated from the arm 39 or shaft 33, for making connection with either of the fixed contacts 43 shown. A spring 45 is provided for causing the switch arm 39 to be normally maintained in balanced 75 relation between the fixed contacts 43.

Electrical connection with the movable contact may be made through a lead 47 when the contact 41 is insulated as above described. Stops 49 are employed in cooperative relation with the arm 51 to positively limit its movement.

5 During movement of the tuning mechanism in either direction by the drive shaft 9, the driving element of the liquid clutch drags the driven element along with it causing an unbalancing of the movable contact arm 39 and the resultant 10 closing of the circuit between the contacts 41 and 43. The circuit remains closed so long as the motion of the driving element of the clutch continues, or at least so long as the motion is above a certain slow speed. Upon cessation of 15 this movement, and after a small time lag, the restoring force of the spring 45 causes the movable contact 41 to assume its normal balanced relation intermediate the fixed contacts 43, the liquid element of the clutch permitting the driven 20 clutch element to slip backward under the action of the spring 45 in a direction contrary to its previous direction with the driving element.

The time lag between the cessation of motion 25 of the drive shaft and the opening of the contact is determined by several factors, such as: viscosity of the liquid in the clutch and the restoring force of the spring 45; spacing of the stops 49 and the contacts 43; and the flexibility of the arm 39 30 and that of the fixed contact support 44, giving a follow-up effect. This time lag is particularly desirable in the case, for example, where the tuning is done in an unsteady manner.

Referring to the electrical system shown in 35 Fig. 3, a cascade tuned radio frequency amplifier 53, 55 has in the input thereof an antenna circuit 57 and adjustable volume control 59 for regulating the amplitude level of incoming signals. The radio frequency amplifier supplies signals to the detector 61 which in turn supplies the audio frequency amplifier 63 and 65 with detected signals. In the output of the audio frequency amplifier stage 65 is connected a loudspeaker 67 of any 40 desired type, for example, the electro-dynamic cone type. Situated at a desirable point in this 45 system as, for example, in the input and the last stage of audio frequency 65, is connected the switch device 29 for inserting an impedance element 69 across said input. While in some instances an ordinary fixed resistance or short-circuit will suffice, particularly in case the tuning 50 consists in moving the tuning elements to certain definite positions, which by previous calibrations have been found to bring in certain stations, I 55 prefer to employ a limiting type of impedance, such as crushed carborundum, a copper oxide rectifier, or a thermionic limiting tube of the type and arrangement shown in Langmuir 1,468,116. Such limiting impedances, when properly connected in the circuit, have the characteristic of permitting the passage of signals below a certain predetermined level but substantially cutting off all impulses above said level. Thus, 60 in manual tuning by ear, it is desirable that all stations tuned in be heard for the purpose of identification, while at the same time limiting the amplitude of the strongest signals so as to avoid unpleasantly loud volume of sounds. Such 65 limiting devices have the disadvantage of distortion of the loud modulated signals or impulses and it is therefore desirable to remove them as soon as the desired station is selected.

70 Although my above novel apparatus has particular utility in connection with the usual form of manual tuning control, it likewise has utility 75

in connection with mechanical preselection or motor-controlled tuning. In the case of actuation of the driving means 7, 9 or 15, in Fig. 1, for automatic tuning of radio apparatus, as by a push-button motor arrangement, it may be sufficient to effect a direct short-circuit of some desired portion of the system, or to use any other method, such as an open circuit as disclosed by the Lieb Patent 1,754,326, for rendering the circuit inoperative during the tuning operation.

Referring to the modification in Fig. 4, I have shown a circuit arrangement, such as a push-pull stage of amplification 70 of a receiving system, provided with means for causing the circuit per se to limit the signal amplitude during tuning. The input transformer 50 is preferably constructed with a high step-up ratio of turns, giving the grid input circuit poor regulation. In other words, the transformer circuit is designed to be easily overloaded. The grids are normally negatively biased to the proper operating voltage by means of a source of grid bias 74, shown here as a battery for purposes of simplification.

A resistor 75 is preferably in series in the bias supply circuit. Upon actuation of the switch 29 by the tuning apparatus, a resistor 76 is connected in series with the resistor 75 and across the source 74, as a potentiometer, causing the grids to be biased to a considerably less negative value. With the resulting low bias the voltage swings of both grids are limited, since the transformer becomes loaded when either grid is made positive with respect to the cathodes. Owing to the close coupling between the two halves of the transformer secondary winding, the voltage generated in the unloaded half is limited to substantially the same magnitude as that in the loaded half. Thus, if the bias is minus 2 volts and the transformer cannot raise the potential of one grid to more than 1 volt positive with respect to the cathodes, or to 3 volts positive with respect to the mean grid potential, the negative swing of the other grid is limited to a like amount.

The decreased negative bias is not applied instantaneously to the grids but operates relatively slowly because of the time required for condenser 81 to discharge through the resistance 76. This gradual change of grid bias prevents the click which would be heard if a direct connection were substituted for the resistance 76. At the same time, the resistance 76 should be low compared with the impedance of the transformer secondary winding, in order that a strong signal shall not build up a negative bias through a rectifier action of the grids. The combination of resistors 75 and 76 and capacitor 81 in effect serves as a filter to prevent an objectionable click which usually results when the direct current circuit of tubes is disturbed, as when the grid bias of an amplifier is changed. In order to provide satisfactory filtering and at the same time keep resistance 76 relatively low, the condenser 81 should be fairly large.

It is desirable that the resistor 75 be of high value, not only to minimize noise when the circuit is broken by the switch 77, but also to make the closing of switch 29 result in a large change in grid bias, and to make the recovery of normal grid bias slow when switch 29 is opened. This sluggishness of recovery or time delay prevents a sudden noise if the switch contacts are accidentally opened for a moment, as during a reversal of movement of the tuning knob, and from this viewpoint it is desirable to cause a slower building up of negative bias, than the

reverse, by proper design of the resistors 75 and 76. By way of illustration, resistance 75 might well be one or two megohms, condenser 81 might be one or two microfarads and resistance 76 would be 5,000 to 10,000 ohms, while the transformer secondary would be wound for an impedance of the order of one-half to one megohm.

Referring to Fig. 4a, I have illustrated a case where a switch 77 is designed to open contact to render effective an amplification reducing device, as for example a resistor 68 adapted to be connected in series in the moving coil circuit 72 of the electrodynamic loudspeaker 67. In this modification, flexible contact elements 44 are provided with stop members 78 to limit the inward movement of said elements. It will be seen that when the switch arm 39 is moved in either direction it carries one contact with it and opens the circuit with the other contact element, thus breaking circuit between the two contact elements, normally bridged by the metallic contact member 41 on the end of the arm 39. The terminals of the moving coil circuit 72 are adapted to be connected to the secondary terminals of the output transformer 85 of the push-pull stage of Fig. 4. Any other desirable element in the system may be provided with means for effecting a reduced or limited output. For example, the detector may be caused to overload during tuning.

Referring to Fig. 5, showing a modified form of the switch actuating mechanism, I have provided a lost motion device between the driving means and the tuner for actuating the switch. As an example the driving means or tuning control knob 7' is so mounted on the shaft 9 as to be free to rotate, within limits, relative to said shaft. Secured to the shaft is a collar or hub 37 carrying arms 51 and 39 as in the structure of Fig. 1. On the end of arm 39 is mounted a metallic contact element 41, and between the other arm 51 and a stud 52 on the flange part of the knob 7', is mounted a spring 45. Secured to the knob 7' are two stop members 49 for limiting the movement of the arm 51, and hence the rotational movement between the dial and shaft. The above mentioned spring 45 is adapted to maintain the knob and dial in such a position on the shaft that the stops 49 are normally maintained substantially equidistant from the arm 51. Similarly the arm 39 carrying the contact element 41 is maintained centrally between the cooperating contact elements 43 mounted on the ends of flexible arms 44 which are in turn mounted on the knob 7' as in the case of Fig. 1. A pin or screw 8 in the dial knob cooperates with a groove 10 in the end of the shaft 9 in sliding relation to prevent relative endwise displacement.

When the receiving apparatus is tuned the operator turns the control knob 7' in one direction and the pressure exerted causes a rotational displacement between the knob and the shaft, effecting a closing of the circuit between contacts 41 and 43. Upon release of the tuning knob the spring 45 causes the latter to move backwards from its previous direction of rotation and to assume a normal position with the contact 41 spaced from both contacts 43. In the foregoing discussion it is assumed that the normal friction exerted by the tuning apparatus, e. g. the condenser bearings, is sufficient to permit the knob 7' to be rotated against the action of the spring 45. If this friction is insufficient, it is obvious to one skilled in the art that additional friction means may be provided.

In the modification of Fig. 5 the condensers may be mounted directly upon the shaft 9, or shaft 9 may be used to drive another shaft carrying condensers in the manner shown in Fig. 1. Although 5 I have disclosed the switch and lost motion means in direct association with the knob 1', it is sometimes desirable to mount the switching apparatus of Fig. 5 on an auxiliary structure in back of the panel of the receiving set in any desirable position between the driving means and the condenser.

From the standpoint of quietness of operation of my apparatus, it is preferred that the limiting means be employed in a part of the circuit which 15 does not substantially disturb the normal flow of direct current. Such an arrangement is shown in Fig. 3. Other circuit portions, which would involve no interruption of the direct current of the amplifier, include the moving coil of a dynamic 20 loudspeaker, illustrated in Fig. 4a, grid to grid or plate to plate of a push-pull amplifier, the antenna circuit, etc. I prefer that the limiter and connecting switch be employed at a point along the system near the output to minimize the amplification between the limiter switch and the 25 final output, for the purpose of further reduction of noise, and because limiting devices can in general be made more effective for moderately high 30 voltages than for very low voltages. In one example a signal voltage of the order of 25 or 30 volts was desirable. In some instances I have found it convenient to couple the limiter to an interstage transformer by means of an extra 35 winding as disclosed in the Holden Patent 1,577,720 and to obtain the desired operating voltage, if not readily available, by a step-up, or in some cases a step-down, ratio of turns. This 40 particular arrangement insures complete isolation from the direct current circuit for reasons above mentioned.

While I have disclosed my invention in combination with a radio tuning apparatus, it is obvious that it may be applied to control any similar apparatus wherein it is desired to control by 45 a movable element a condition of operation of such apparatus other than the operation normally controlled by said element, and at any point in the range of movement of said element, 50 without the performance of any additional operation such as a different movement of the said element. Furthermore, the apparatus is automatically caused to operate in its normal manner at the end of the movement of said element without any conscious effort on the part of the operator.

In accordance with another phase of my invention, I have provided, as above described, means for inserting and removing a limiter device 55 in a receiving system, while according to another phase of my invention I have provided means for changing a device or a circuit portion

already in the system, from its normal condition to a limiting condition.

Although I have shown and described certain specific embodiments of my invention, I am fully aware that many modifications thereof are possible. My invention, therefore, is not to be restricted except insofar as is necessitated by the prior art and by the spirit of the appended claims. 5

I claim as my invention:

1. In an amplifying system having thermionic devices in cascade, means for tuning one of said devices within a range of wave lengths, unitary means for changing another of said devices from its normal operating condition to a limiting condition in response to and during movement of 15 said tuning means, and for restoring said last named device to said normal condition upon cessation of said tuning movement, and means for effecting an appreciable time delay between said restoring operation by said means, and the attainment of said normal condition by said last named device.

2. In a cascade thermionic amplifier system having a series of amplifiers, means for adjusting the frequency response characteristic of one 25 of said amplifiers, means for changing another of said amplifiers from its normal amplifying condition to a limited amplifying condition comprising a source of voltage for an electrode of 30 said last named amplifier, a switch for changing the voltage applied to said electrode, slip-clutch means connected with said first named means for operating said switch during the adjustment of said first named amplifier, and a filter for suppressing electrical disturbances resulting from 35 the operation of said switch.

3. In a radio apparatus, the combination with a moveable control means therefor, of a clutch having a driving member connected with said control means to move therewith, a driven member, viscous fluid means for coupling said driven member to said driving member, and electrical circuit controlling means connected to said driven member to be actuated by movement thereof, whereby said circuit controlling means is rendered operative during movement of said moveable control means and rendered inoperative upon cessation of said movement. 40

4. In a radio receiving system, the combination of a movable means for effecting a tuning operation of said system within a range of wave lengths, means for limiting the volume of reproduced signals provided by said system, a switch for connecting said means in operative relation in said system, and a clutch means having a viscous fluid interposed between its driving and driven elements, further to provide a connection between said tuning means and said switch, whereby said switch is automatically operated during motion of said tuning means and is released upon cessation of said motion. 50

EDWARD WASHBURN KELLOGG.
